BY

V. H. Lockwood.

ATTORNEY.

UNITED STATES PATENT OFFICE.

CORNELIUS P. KENTON, OF ANDERSON, INDIANA, ASSIGNOR TO KENTON REGULATOR COMPANY, OF ANDERSON, INDIANA, A COPARTNERSHIP.

GAS-REGULATOR.

No. 890,238.

Specification of Letters Patent.

Patented June 9, 1908.

Application filed October 4, 1907. Serial No. 395,848.

To all whom it may concern:

Be it known that I, CORNELIUS P. KENTON, of Anderson, county of Madison, and State of Indiana, have invented a certain 5 new and useful Gas-Regulator; and I do hereby declare that the following is a full, clear, and exact description thereof, reference being had to the accompanying drawings, in which like letters refer to like parts.

10 The object of this invention is to improve the construction and operation of gas regulators whether for high pressure service or low pressure service.

One feature of the invention consists in a 15 peculiarly balanced valve mechanism, two valves being mounted on opposite sides of a diaphragm-controlled lever, so that the pressure of the gas on the high pressure side of said valves will counteract each other.

20 Another feature of the invention consists in the provision of a rocking valve or one that is automatically adjustable to its seat.

Another feature of the invention consists 25 in the means for mounting the valve-controlling lever.

Another feature of the invention consists 30 in providing means for preventing any particles of mercury from being deposited upon the diaphragm. Heretofore mercury particles have been deposited upon the diaphragm gradually so as to materially alter 35 the action of the diaphragm and the operation of the device.

This invention prevents the mercury loading 35 the diaphragm.

The nature of the invention will be understood from the accompanying drawings and the following description and claims.

In the drawings Figure 1 is a central vertical section through the device in line with the valve-actuating lever. Fig. 2 is a horizontal section on the line 2--2 of Fig. 1, parts being broken away.

In detail the casing of the device is formed 45 of a bottom portion 10, top portion 11, a mercury seal portion 12, which when united, provide a low pressure chamber 16 with a gas outlet 17, a low pressure diaphragm chamber 18, a mercury chamber 19, an atmospheric pressure chamber 20, and a mercury-catching chamber 21. Between the 50 two parts 10 and 11 leather 22 is secured that forms a part of the diaphragm which is com-

bined with the diaphragm plate 23 above and the plate 24 below secured by the screw 25. 55 The diaphragm is downwardly pressed by a spring 26, the tension of which is controlled by a screw 27. From the plate 24 ears 29 extend downwardly that are pivoted to one end of a valve lever 30, which is fulcrumed on a pin 31. The longer end of said lever lies in the diaphragm chamber 18 and the short end extends into the low pressure chamber 16. These two chambers 16 and 18 are in communication with each other. One end 60 of the pin 31 projects into a socket in the inner side of the casing 10 and the other end of the pin abuts against a screw 32, whereby said pin is held in place or removed.

Into the small end of the lever 30 a screw 70 valve stem 33 extends that has a nut 34 on its upper end, and the lower end 35 is oval and fits in a correspondingly oval-shaped recess in the upper part of the substantially flat-faced valve 36 so that the valve can rock or 75 have some movement independently of the valve stem. A screw 37 enters the bottom of the valve and screws up against the oval end 35 of the valve stem so that the relation between the valve and valve stem can be ad- 80 justed and predetermined. The other valve 40 is in a position the reverse of the valve 36, but has a similar oval-shaped socket for the oval-shaped lower end 41 of a valve-stem 42 that is mounted in the lever 30 on the side of 85 the pivot 31 opposite the other valve stem 33. The valve 40 has a similar screw 37 for adjusting it on its valve seat. There is an opening in the casing below the valve 40 that is closed by a plug 44 to render said valve ac- 90 cessible. The partition 45 in the mercury chamber is held in place by a screw 46 that screws into a partition 47 which separates the chambers 18 and 20. A projecting shell 48 extends from said partition 47 so as to 95 partially check any particles of mercury that might be blown out from the mercury chamber. Such particles as would pass this shell 48 would go up through the passageway 50 into the chamber 21 that communicates with 100 the low pressure chamber above the dia- phragm by a passageway 52. The upper end of the chamber 21 is closed by a plug 53. The lower end of the chamber 21 tapers 105 downwardly so that such mercury particles as would enter said chamber would by grav-

ity return and drop down into the mercury chamber 19. 59 is an opening for the outside air.

What I claim as my invention and desire to secure by Letters Patent is:

1. A gas regulator provided with a diaphragm and a low pressure chamber below the diaphragm, an atmospheric chamber above the diaphragm, an outlet passageway 10 leading from the low pressure chamber that is in communication with the chamber above the diaphragm, a mercury seal between the low pressure chamber and the outlet and below the passageway to the chamber above the diaphragm, and means for preventing the mercury from passing into the chamber above the diaphragm and depositing upon the diaphragm.
2. A gas regulator provided with a diaphragm, a low pressure chamber below the diaphragm, an atmospheric pressure chamber 15 above the diaphragm 20

ber separated by a partition from the low pressure chamber, a mercury seal between said two chambers, an atmospheric pressure chamber above the diaphragm, and a mercury 25 catching chamber above said first mentioned atmospheric pressure chamber and discharging downwardly therein and in communication with the chamber above the diaphragm, whereby said mercury catching chamber will 30 catch all mercury particles that may be blown from the mercury seal and prevent the same from entering the chamber above the diaphragm and being deposited on the dia- phragm substantially as set forth.

In witness whereof, I have hereunto affixed my signature in the presence of the witnesses herein named.

CORNELIUS P. KENTON.
